UNITED STATES PATENT OFFICE.

FRANK S. RHOADS, OF AURORA, ILLINOIS.

UNIVERSAL JOINT.

1,255,792.

Specification of Letters Patent. Patented Feb. 5, 1918.

Application filed March 13, 1917. Serial No. 154,514.

To all whom it may concern:

Be it known that I, FRANK S. RHOADS, a citizen of the United States, residing at Aurora, in the county of Kane and State of Illinois, have invented new and useful Improvements in Universal Joints, of which the following is a specification.

This invention comprehends improvements in universal joints and relates particularly to incased joints of this nature having a driving yoke and a driven yoke connected by studs or journals to a ring.

One of the objects of the invention is to provide a universal joint of this type which is of extremely simple construction, which has no complicated parts and which may be easily and quickly assembled and disassembled.

Another object of the invention is to generally improve universal joints to render them more practical, useful and commercially desirable.

With these and other objects in view as will become more apparent as the description proceeds, the invention consists in certain novel features of construction, combination and arrangement of parts as will be hereinafter fully described, illustrated and claimed.

30 In the drawings,

Figure 1 is a longitudinal sectional view through my improved universal joint.

Fig. 2 is a longitudinal sectional view on the plane at right angles to the plane of Fig. 1.

Fig. 3 is a transverse sectional view through the joint on the plane of line 3—3 of Fig. 2.

Fig. 4 is a sectional view on the plane of line 4—4 of Fig. 1.

Fig. 5 is a longitudinal sectional view partly in elevation showing a somewhat modified form of joint.

Fig. 6 is an enlarged transverse sectional view on the plane of line 6—6 in Fig. 5.

Fig. 7 is an enlarged detail view of the bushing retaining ring shown in Fig. 5.

Fig. 8 is a fragmentary view in elevation showing portions of the main connecting ring and the retaining ring.

Fig. 9 is a detail perspective view of one of the bushings used with the retaining ring.

Fig. 10 is a fragmentary sectional view illustrating a modified form of journal, and

55 Fig. 11 is a fragmentary detail view of the connecting ring shown in Fig. 1.

Referring in detail to the drawings by numerals, 1 designates a hub having a peripheral flange 2 on one end thereof which is bolted or otherwise secured to a knuckle 60 or yoke generally designated 3 having a base plate or disk 4 on which are formed a pair of arms 5. The hub is connected to a shaft 6.

The yoke 3 co-operates with a yoke or knuckle 7 having arms 8 formed integral with a hub 9. Keys or ribs 10 are formed on the interior of the hub 9 and engage the ribs or keys 11 on the shaft 12 which has a sliding movement within the hub 9.

70 The arms of the two knuckles or yokes extend into a connecting ring 13 and are pivotally connected thereto. The interior surface of the ring is formed at four points with flat faces for engagement with the 75 outer faces of the yoke arms as best shown in Fig. 3.

The arms 5 of the yoke 3 are connected to the ring 13 by a hollow pin 14, the ends of which extend through openings in the ring 80 and form journals. The pin may be closed at its ends by plugs 15 and is formed with oil passages 16. Oil or grease may enter the interior of the pin 14 through the openings 17. Bushings 18 are carried by the 85 ring and encircle the terminal portions of the pin as clearly shown. To lock the pin against longitudinal and rotational movement, I employ a key or lock pin 19 which may be driven into position through the base 90 plate 4 as shown in Fig. 1.

The arms 8 of the yoke 7 are preferably formed with integral studs or journals 20 which may be slipped into position within the sockets or openings 21 of the ring 95 through the slots 22. After the journals 20 are in position within the ring openings 21, bushings 23 are driven into position and lock the journals in place. To counteract the weakening effect of the entrance slots 22, 100 I form the ring with an enlargement 24 opposite each of the slots as best shown in Fig. 11. The journals 20 are formed with oil passages 25 which may be closed at their outer ends by plugs 26 and which communicate with the oil passages 27.

A casing for the joint is formed in sections 28 and 29. The section 28 is bolted to the base plate 4 of the yoke 3 and carries a packing strip 30 which bears tightly 110 against the casing section 29. This last mentioned section is held in engagement

with the packing strip 30 by an expansive helical spring 31 which bears at one end against a washer 32. To prevent an escape of oil and grease from the hub 9, I provide on the outer end of this hub, a ring or nut 33 which engages a washer 34 bearing against a packing ring 35.

In Fig. 5 I have illustrated a modified form of my invention. In this form, a hub 10 36 is connected to a yoke 37 having arms 38. The yoke 37 coöperates with a yoke 39 having arms 40. Each of the yoke arms is formed with an integral journal 41 which fits within an opening 42 in the connecting ring 43. The journals may be slipped into place through slots 44 in the ring and after they have been positioned, they are secured against displacement by bushings 45 of a larger diameter than the width of the slots 20 44. To hold the bushings in position, I employ a retaining ring 46 which is bolted or otherwise secured to one side of the connecting ring 43 and which is formed with a circumferential laterally projecting flange 47 25 which seats in an annular groove formed in the periphery of the ring 43 and in the notches 48 formed in the side of the bushings adjacent the outer end.

The ring, besides retaining the bushings 30 in position, acts as a reinforcing member for the ring 43.

A casing 49, having the sections 50 and 51 constructed similar to the sections of the first described casing, incloses the modified 35 joint and acts as a dust guard and grease and oil retainer.

Instead of forming the journals integral with the yoke arms, they may be formed 40 separate therefrom and connected thereto as shown in Fig. 10. Here the journal 52 is driven into the arm 53 and is reduced adjacent its outer end portion to accommodate a bushing 54. The ring 55 is formed with an opening 56 equal in diameter to the 45 larger diameter of the journal so that it may be slipped into position from the exterior of the ring.

From the foregoing description taken in connection with the accompanying drawings, 50 it will be apparent that I have provided a universal joint which is susceptible of various modifications, which is extremely simple and practical, which is very efficient in operation, and which may be easily assembled and disassembled.

While I have shown and described the preferred embodiments of my invention,

it will be clearly understood that I do not wish to be limited to this construction, but may make such changes as will fall within 60 the scope and spirit of the invention as claimed.

What I claim is:—

1. A universal joint including a ring, yokes having arms extending into said ring, 65 the ring being formed with journal openings, journals connecting said arms with the ring, the ring having entrance slots to permit the journals to be engaged with the journal openings, and bushings surrounding 70 the journals, said bushings being of a larger diameter than the width of the slots.

2. A universal joint including a connecting ring formed with journal openings therein, yoke members having arms extending into said ring, journals formed on the arms of one of said yoke members, the ring being provided with entrance slots to permit said journals to seat in the journal openings, bushings surrounding the journals 80 of a greater diameter than the entrance openings, and a pin connecting the arms of the other yoke member with the ring.

3. A universal joint including a connecting ring having journal openings and slots 85 communicating therewith, yoke members having arms extending into said ring, journals formed on the arms of one of said yoke members and fitting within said journal openings, bushings surrounding the 90 journals of a greater diameter than the width of said slots, a pin connecting the arms of the other yoke member with said rings, and means for holding said pin in position.

4. In a universal joint, a connecting ring, bushings therein, yokes, journals carried by the yokes and extending into said bushings, and a retaining ring secured to one side of said connecting ring, the retaining ring being formed with a lateral flange and the bushings being formed with notches in one side adjacent their outer ends to accommodate said flange.

5. In a universal joint, a connecting ring 105 having openings, yokes, journals on said yokes received within said openings, the ring being also provided with entrance slots, for said journals, bushings surrounding the journals of a greater diameter than the 110 width of said entrance slots and a retaining ring for securing said bushings in position.

In testimony whereof I affix my signature,
FRANK S. RHOADS.
